PORTABLE RADIO

Taka Y. Takei, 145 Wai Yip St., Viet Shing Factory,
Kowloon, Hong Kong

Filed June 14, 1972, Ser. No. 262,723

Term of patent 3½ years

Int. Cl. D14—03

U.S. Cl. D56—4 B

FIG. 1 is a front elevational view of a portable radio, showing my new design;

FIG. 2 is a right side elevational view;

FIG. 3 is a rear elevational view; and

FIG. 4 is a left side elevational view thereof.

I claim:

The ornamental design for a portable radio, as shown and described.
